(57) **CLAIM**

The ornamental design for a dispensing closure, as shown and
described.

DESCRIPTION

FIG. 1 is a front perspective view of the dispensing closure in
accordance with the present invention;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is bottom view thereof;

FIG. 8 is a cross-sectional view thereof as taken along line
8—8 in FIG. 5; and,

FIG. 9 is a front perspective view of the dispensing closure
with the lid closed.

The broken lines in the drawing depict environmental subject
matter only and form no part of the claimed design.
